UNITED STATES PATENT OFFICE

163,013

EXTENDABLE AND PORTABLE BAR

Charles J. Zeman, Kalamazoo, Mich.

Application March 31, 1950, Serial No. 8,886

Term of patent 14 years

(Cl. D33—19)

To all whom it may concern:

Be it known that I, Charles J. Zeman, a citizen of the United States, residing at 201 Creston Avenue, Kalamazoo, in the county of Kalamazoo and State of Michigan, have invented a new, original, and ornamental Design for an Extendable and Portable Bar, of which the following is a specification, reference being made to the accompanying drawings, forming a part thereof.

In the drawings:

Figure 2 is a substantially rear perspective view of the extendable and portable bar, with the bar extended to its full length.

Figure 4 is an end elevation view of said bar in the extended position.

I claim:

The ornamental design for an extendable and portable bar, substantially as shown and described.

CHARLES J. ZEMAN.
